UNITED STATES PATENT OFFICE.

HENRY C. EMRICH, OF WASHINGTON, DISTRICT OF COLUMBIA.

COMBINATION HOUSEHOLD CHAIR, STEPLADDER, ETC.

Application filed February 20, 1925. Serial No. 10,668.

This invention relates to a combination household article, which may be utilized for a variety of purposes, such as a chair, step-ladder, wash-bench, ironing board support, window seat, and the like.

The primary object of the invention is the provision of a novel combination article, normally simulating a chair, but embodying extensible and adjustable arrangement of parts, by which the article may be made to assume different stable supports, such as those above and hereinafter enumerated.

A further object of this invention is the provision of an improved combination household article, embodying novel supporting and retaining framework to enable the parts thereof to be stably supported in a variety of positions, for a variety of purposes.

A further object of this invention is the provision of a chair embodying an extensible seat, and novel means to hold the same in an extended or collapsed position.

Other objects and advantages of this invention will be apparent during the course of the following detailed description.

In the accompanying drawings, forming a part of this specification, and wherein similar reference characters designate corresponding parts throughout the several views,

Figure 1 is a perspective view showing the improved article, as a chair.

Figure 2 is a cross sectional view taken substantially on the line 2—2 of Figure 1, showing more particularly the seat arrangement and the retaining means therefor.

Figures 3 and 4 are enlarged fragmentary cross sectional views taken substantially on their respective lines in Figure 2 of the drawings.

Figure 5 is a view showing the improved article with the parts thereof positioned to support an ironing board.

Figure 6 is a vertical sectional view taken through the improved article, with the seat thereof extended to provide a tub or other bench support.

Figures 7 and 8 are views showing the parts arranged respectively to provide a window seat or scaffold, and a step-ladder of the improved article.

Figure 9 is a perspective view of a seat and leg reinforcing brace and guide member.

In the drawings, wherein for the purpose of illustration is shown only a preferred embodiment of the construction of the improved combination article, the letter A may generally designate the article, which may include an extensible seat construction B; front leg frame C; back and rear leg construction D; front retaining frame E; and rear retaining frame F.

In the improved article the seat B is of novel construction, comprising front and rear slidably connected sections 10 and 11 respectively, to which the front leg and back supporting structures C and D are respectively connected.

The front leg construction C and the front seat section 10 are rigidly connected. The front leg construction C comprises the corner legs 13 and 14, connected in a rigid relation by a lower brace 15, and connected in rigid relation at their upper ends by means of a cross brace 16 disposed in a vertical plane with its outer surface flush with the front edges of the legs 13 and 14. The front seat section 10 comprises the inner side rails 18 and 19, which are rigidly connected in right angled rearwardly extending relation with the legs 13 and 14 respectively, by means of the metal connecting pieces or members 20, detailed in Figure 9 of the drawings. The rails 18 and 19 are disposed in vertical planes, and at their front ends overlap the inside surfaces of the legs 13 and 14. At their rear ends the inner rails 18 and 19 may be connected by a cross piece 25, illustrated in Figure 6 of the drawings. The front seat section 10 may furthermore comprise the front horizontal slat or portion 27 of the seat, although the remaining slats of the seat are connected to the rear section 11,

Figure 1 is a perspective view showing the improved article, as a chair.

Figure 2 is a cross sectional view taken substantially on the line 2—2 of Figure 1, showing more particularly the seat arrangement and the retaining means therefor.

Figures 3 and 4 are enlarged fragmentary cross sectional views taken substantially on their respective lines in Figure 2 of the drawings.

Figure 5 is a view showing the improved article with the parts thereof positioned to support an ironing board.

Figure 6 is a vertical sectional view taken through the improved article, with the seat thereof extended to provide a tub or other bench support.

Figures 7 and 8 are views showing the parts arranged respectively to provide a window seat or scaffold, and a step-ladder of the improved article.

Figure 9 is a perspective view of a seat and leg reinforcing brace and guide member.

The member 20 is preferably constructed of a single piece of metal, stamped or otherwise formed to provide the leg attaching portion 29 and the rail attaching portion 30. The leg attaching portion 29 comprises the plate 31 having the right angled side flanges 32 extending therefrom. The leg attaching portion 29 is placed at the inside surface of the leg 13, or 14, as is illustrated in the drawings, and the flanges 32 are just sufficiently spaced that they may overlap the front and rear edges of the leg. The seat rail attach-

ing portion 30 is elongated, and integrally connected at the top edge of the leg attaching portion 29, in laterally extending relation therefrom. It comprises the plate 33 adapted to be attached to the outside surface of the rail 18 or 19, and along the upper edge thereof provides the outwardly facing guide flange 34, in right angled relation thereto, which projects beyond the plane of the outside surface of the respective rail, for reinforcing and guiding the sliding movement of the seat section 11, as will be subsequently described. Both the plate portions 31 and 33 are provided with suitable openings therein for receiving attaching screws or bolts 35, substantially as is illustrated in the drawings.

The rear seat section 11 comprises the outer side rails 36 and 37, connected in vertical and in parallel spaced relation by means of the transverse seat slats 38. The side rails 36 and 37 slide outwardly in parallel abutting relation with the outer surfaces of the rails 18 and 19 of the front seat section 10, and at their inside surfaces the rails 36 and 37 are longitudinally grooved, at 40, as is illustrated in Figures 4 and 6 of the drawings, to slidably receive therein the right angled guide flange 34 of the brace member 20. The end edges of the transverse seat slats 38 are spaced inwardly a short distance from the planes of the outer surfaces of the rear section rails 36 and 37, to provide side grooves 45^a so to speak, adapted to receive the side bars of the front retaining frame E, as will be subsequently described, and as is plainly shown in Figures 2 and 4 of the drawings. The slats 38 are preferably disposed so that spaces 42 are provided therebetween, for a purpose which will be subsequently described. The rear edges of the side rails 36 and 37, may be rounded, as is illustrated at 43 in Figure 6 of the drawings, to permit the pivotal action of the back and rear leg construction D upon the seat section 11, for a purpose which will be subsequently described. At the lower edges the rails 36 and 37 may be provided with window sill engaging blocks or pieces 45, which may be provided with lower edges 46 disposed diagonally to the plane of the seat. In assembled relation with the seat section 10, the outer surfaces of the rails 36 and 37 of the section 11 are preferably disposed flush with the outer surfaces of the legs 13 and 14.

Referring to the back and rear leg construction D, the same is pivotally connected between its ends at the rear end of the seat section 11. This construction D comprises the side frame members or supports 50 and 51, of any approved nature, which at their lower edges 52^a are preferably rounded. These frame members 50 and 51 are disposed at opposite sides of the seat construc-

tion B, and pivoted thereto intermediate their ends by means of the axle or shaft 52, which is horizontally disposed thru the seat rails 36 and 37, and is detachable therefrom; bolts 53 being provided at the ends 70 thereof for holding the rails 50 and 51 in place. These members 50 and 51 below the pivots 53 really provide legs 55 for the article A, and upwardly of the pivot shaft 52 provide portions 56 of the back. Transverse 75 rungs or braces 57 are provided in rigid connection between the members 50 and 51 both below and above the seat structure B, the same being diagonally disposed so that when the back and leg construction D is disposed at 80 an angle to the vertical, the said rungs 57 will be disposed in a horizontal plane, to form a step-ladder, as is illustrated in Figure 8 of the drawings. The topmost rung or brace 57^a is secured at the top edge of the rails 50 and 51, and has a leaf 58 hingedly connected forwardly thereto, by means of hinges 59, so that in normal position the leaf 58 will hang downwardly, and in non-projecting relation when it is desired to 85 use the article A as a chair. The leaf 58 therefore really forms a part of the topmost rung 57^a, and at its lower front edge the same is grooved upwardly, at 60, and the leaf portions 61 of the hinges project beyond the said groove 60 for cooperating in a retaining relation with the front retainer frame E, when the device is used as a step-ladder, as is illustrated in Figure 8 of the drawings. The legs 55 are provided with 90 a cross brace 51^a just below the seat slat 38^a, having a beveled top edge adapted to engage beneath said slat to brace the structure D in inclined position.

Referring to the front retaining frame E, 105 the same preferably comprises the side bars 63 and 64, which at their forward ends are provided with the inwardly and axially aligning bearing extensions 65, which as is illustrated by the dotted lines in Figure 2 110 of the drawings, extend through the upper ends of the legs 13 and 14, and through the inwardly positioned rails 18 and 19, as a means of forming a bearing for pivotally 115 swinging the frame E. The bars 63 and 64 115 at their free swinging end are connected by the transverse bar portion 66 integral therewith, which has a downwardly extending lug 67 thereon adapted to seat in the spaces 42 between the slats 38. In its collapsed position upon the seat structure B, the frame E has the side bars 63 and 64 lying in the side grooves 45 of the seat, as is illustrated in Figures 2 and 3 of the drawings, and the front transverse bar portion 66 also is 125 adapted to lie in the space 42 between the slats 38, or at the extreme rear end of the rearmost slat 38^a, in the position illustrated in Figure 2 of the drawings. Thus, the bar portions 63, 64, and 66 of the frame E are 130

adapted to lie in the same plane as the slats 38 of the seat structure B, when the frame E is collapsed. To afford additional stability to the frame E, at the free swinging end thereof, but primarily for the purpose of providing a support for an ironing board K, as is illustrated in Figure 5 of the drawings, a transverse brace and support bar 68 is integrally connected or welded at its ends to the bars 63 and 64, in parallel relation just slightly inwardly of the end transverse bar 66, but in an elevated plane with respect to the plane in which the bars 63, 64 and 66 lie, so that the support bar 68 will lie on top 15 of a slat 38 when the retaining frame E is positioned in collapsed relation upon the seat section 11, and as is illustrated in Figure 2 of the drawings.

The retaining frame E includes, at each side thereof adjacent the bearing extension 65, a forwardly and downwardly extending J-shaped hook 70, adapted to cooperate with a laterally projecting pin or catch member 71 fixedly carried by the legs 13 and 25 14, and for the purpose of supporting the frame E in an upwardly extending slightly forwardly inclined position, when the article A is used as an ironing board support, as is illustrated in Figure 5. It is thus 30 readily apparent that the frame E may be swung from its seat collapsed position upwardly and forwardly, and the hooks 70 will approach the laterally extending pins 71 and engage the same when the plane of the frame E is in the position illustrated in Figure 5, and prevent any further swinging or tipping movement of the frame E, so that it is in position to support the ironing board.

The retaining frame E furthermore includes the rearwardly extending and upwardly facing substantially J-shaped hooks 73, at each side thereof adjacent the bearing extensions 65, and preferably integral 45 with the hook 70, the same being relatively longer than the hook 70, and facing in the opposite direction for the purpose of cooperation with laterally extending pin projections 75 carried by the front ends and at 50 the outer sides of the rails 36 and 37 of the rear seat section 11. The cooperation of the hooks 73 against the pins 75 serves several functions, the most important of which is to lock the seat sections 10 and 11 in a collapsed position, when the frame E is positioned upwardly in a plane slightly inclined to the rear, and in engagement in the groove 60 of the leaf 58, when the device A is used as a step-ladder, and to prevent extension 55 of the seat sections with respect to each other, and to stabilize the upper end of the construction D, when it is used as a ladder. The hooks 73 it will also be noted are shaped to have a cam action against the pins 75, so 60 that the sections 10 and 11 may be absolute-

ly drawn into their most collapsed position, if it is otherwise difficult to draw the same in such position.

Referring to the rear retaining construction F, the same is primarily provided for the purpose of bracing and adjustably fixing the position of the back and leg construction D with respect to the seat B, and particularly the section 11 of the seat B. This retaining construction F comprises the pawl or retaining frame 80; metal brace and bearing plates 81 and 82 connected to the rails 50 and 51 of the construction B respectively; and rack devices 83 and 84 attached at opposite sides of the section 11 of the seat construction B, for cooperation with the pawl or retaining frame 80.

The rack plates or devices 83 and 84 are of analogous construction, including the top plate portion 86, adapted to rest upon the top at the ends of the slat 38^a, and providing upwardly extending spaced teeth 87, in the space between which the pawl bar or frame 80 is adapted to cooperate. Each of these retaining devices 83 and 84 are provided with end flanges extending downwardly about the slat 38^a, and the same is angled into the side grooves 45^a of the seat B, as is illustrated in Figure 3 of the drawings, to permit the collapsing of the bar portions 63 and 64 of the retaining frame E therein, and is further extended as a plate portion 90 downwardly along the outer side of the rails 36 and 37 of the seat section 11; these portions 90 being secured as 95 by screws 91 to the rails 36 and 37, as is illustrated in Figure 1 of the drawings, and being provided with openings for receiving the pivot shaft 52 in bearing relation 100 therein. This provides a reinforced construction for the support of the shaft 52.

The bearing plates 81 and 82 are of analogous formation, the same being secured as by screws 94 at the inside surfaces of the rails 50 and 51, and preferably having lateral flanges overlapping the front and rear edges of the rails 50 and 51, as is illustrated in Figures 1 and 2 of the drawings. Furthermore, each of these plates 81 and 82 provides a rearwardly projecting bearing 110 extension 95, into which the aligning spindle ends 96 of the retaining frame 80 bear for pivotal movement. The bearing plates 81 and 82 extend for a considerable distance above and below the pivot shaft 52, providing openings for support of said pivot shaft 52. In this relation of parts the plate portions 90 of the rack devices 83 and 84 are in surface engagement with the bearing plates 81 and 82, so that there is a metal to metal 115 contact at the pivotal connection of the construction D with the seat structure B.

The pawl or retaining frame 80 is of novel construction. It is formed in order to be laterally adjustable for a cooperative and 120 125 130

rigid connection with the rack devices 83 and 84. It comprises the transverse bar portion 98, which is normally positioned as to be diagonally disposed over the seat slat 38^a. At one end thereof adjacent the rack bar or device 83 the same is provided with a plurality of rearwardly stepped portions 99. At the opposite end thereof the bar 98 is provided with the forwardly stepped portions 100 for cooperative engagement with the teeth of the rack bar device 84. Rearwardly extending parallel side bars 102 and 103 are provided at opposite sides of the frame F, connected with the step portions 99 and 100 respectively, and at the opposite ends of these bars 102 and 103 the outwardly extending spindle extensions 96 above mentioned are provided for bearing in the portions 95 of the metal plates 81 and 82 above mentioned. The side bars 102 and 103 are spaced inwardly from the bearing plates 81 and 82 so that the entire frame 80 may be laterally shifted to vary the positions of the stepped portions 99 and 100 with respect to the teeth of the rack portions 83 and 84. When the stepped portions 99 and 100 are in engagement between the teeth of the rack devices 83 and 84, however, the frame 80 is rigidly positioned against any further lateral movement, and cannot become easily displaced.

Referring to a number of uses to which the improved article A may be put, when used as a chair the sections 10 and 11 of the seat B are slidably collapsed with the front edge of the rails 36 and 37 in abutment with the inside edges of the legs 13 and 14, as is illustrated in Figure 1 of the drawings. In this position the frame E is collapsed over the seat B, and locks the sections 10 and 11 against movement, since the outer cross bar 66 of the frame F engages at the rear edge of the seat slat 38^a, as is illustrated in Figure 2 of the drawings. As to the back and leg construction D the same is rigidly affixed with respect to the seat B, by means of having the frame 80 engage in a locked position with the teeth of the rack devices 83 and 84.

When it is desired to use the improved article A as an ironing board support, as is illustrated in Figure 5 of the drawings, the front retaining frame E is swung upwardly, releasing the sections 10 and 11 of the seat B, so that they may be slidably extended into the position illustrated in Figure 5, and in this position the frame E is supported in its upward and forwardly inclined relation by means of engagement of the hooks 70 with the pin 71. The ironing board K may then be slipped into the space between the bars 66 and 68 of the frame E, resting on the latter, and at a point further along the ironing board K rests upon the top rung 57^a of the back and leg construction D. The con-

struction D is braced in its forwardly inclining position by means of proper adjustment of the pawl frame 80 with the rack devices 83 and 84, and thus the article A is rigidly positioned for a stable support of 70 the ironing board K.

When the device A is to be used as a wash-tub support, or analogous bench, the sections 10 and 11 of the seat B are slidably extended, by releasing the frame E to permit such 75 slidable extension, and after the bench of desired length has been provided, the frame E is swung downwardly again to lock the sections 10 and 11 in their desired extended relation. This locking operation is effected because of the fact that the lug 67 of the retaining frame E, as well as the front bar 66 of said retaining frame E engages into the spaces 42 between any of the slats 38. The construction D forming the back 85 and rear leg is locked to the seat section 11 similar to that above described when providing a chair.

It is apparent from the foregoing description that the sections 10 and 11 may be 90 slidably extended because of the fact that the rails 36 and 37 in the section 11 are grooved to receive the angle guide flange 40 of the section 10, as is illustrated in the 95 drawings.

When the improved article A is to be used as a window seat, or as scaffolding for a building structure, and as is illustrated in Figure 7 of the drawings, the article A is disposed through the opening 110 of a window construction or casing L. In view of the width of the window casing it may be necessary to extend the sections 10 and 11, and this is accomplished in the manner above described, and the sections 10 and 11 100 locked in such position by means of the retaining frame E. The window seat B straddles the sill of the window casing L with the front legs 13 and 14 in abutment with the inside wall or sill of the window. The back and rear leg construction D may have to be slightly adjusted, and is preferably tipped outwardly at an inclination to the vertical, until the lower end of the rear legs 105 55 engage the outside surface 112 of the 115 wall of the building construction. In this position the rear legs are locked with respect to the seat B by means of the pawl frame 80, as above described. In this use of the device the supporting blocks 45 also 120 play an important part, since the beveled or lower edges 46 thereof rest upon the top sloping surface 113 of the sill block 114, so that the seat B of the article A may be horizontally positioned. Thus, the parts of the 125 article A when used as a window seat or support, are rigidly connected in a position which will not prevent of any accidental displacement from the window casing or 130 the wall of the window construction.

- One of the most important uses of the device A is that it may be arranged to provide a very stable step-ladder. To this end the sections 10 and 11 of the seat structure 5 are slidably collapsed, and the front retaining frame E swung upwardly until the rearwardly extending hooks 73 engage in a cam and a retaining action against the pins 75 of the seat section 11, and in this position 10 the frame E is swung upwardly to its maximum extent, although slightly inclining to the rear. The upper cross bar 66 of the frame E is received in the groove 60 of the ladder leaf 58, with the latter disposed in 15 the same plane as the top rung 57^a. In this position of parts the back and rear leg construction D, of course, having been swung forwardly at an inclination to the vertical, the same is locked in such position by means 20 of the pawl frame 80 of the rear retaining construction F, and as is illustrated in Figure 8 of the drawings. This positions the rungs 57 and 57^a in parallel relation, and in 25 horizontal position with respect to the seat slat 38^a, so that the latter may also be used as a rung for the ladder.

From the foregoing description of this invention it is apparent that a novel type of combination household article has been provided, which is susceptible of use for a variety of purposes, and which embodies a novel and compact arrangement of parts which may be adjustable and rigidly connected to accurately and stably position the 30 parts against liability of accidental displacement.

Various changes in the shape, size, and arrangement of parts may be made to the form of invention herein shown and described, without departing from the spirit of the invention or the scope of the claims.

I claim:

1. In a device of the class described the combination of a seat structure including a pair of sections, means slidably connecting the sections for collapsed or extended positioning with respect to each other, leg supporting means for said sections, one of said sections having spaced slats as a part of the seat structure thereof, and a locking frame pivotally carried by the other section adapted to extend into the spaces between said slats for locking the sections against relative movement.
2. In a combination device of the class described a seat structure including a pair of slidably extensible sections, leg supporting means carried by said sections, one of said sections having a plurality of seat slats in spaced relation, and a retaining frame pivotally connected to the other section including side bars extending from the pivotal connection thereof with said section, the free end thereof providing a cross bar, the section with said spaced slats having grooves

therealong at the sides thereof adapted to receive the side bars of the retaining frame when it is collapsed upon said section upon which the slats are provided and so that the cross bar thereof extends into a space between adjacent slats to lock the sections together.

3. In a device of the class described the combination of a seat structure including a pair of extensible sections, a front leg supporting construction for one of said sections, metal connecting braces each including a plate portion for connection to said front leg construction and an integral plate portion for connection to said seat section, said last mentioned plate portions having laterally extending guide flanges projecting from the seat section to which attached and said other seat section having grooves therein for slidably receiving said guide flanges to slidably connect said sections, and leg supporting means for the seat section in which said grooves are provided.

4. In a device of class described the combination of a seat, leg supporting means for the seat including a movable leg construction pivoted to the seat at an end thereof, a pair of rack devices providing spaced teeth located on top of said seat at opposite sides thereof, and a pivoted pawl frame connected to said movable leg construction above the seat for adjustable connection with the teeth of the rack devices to hold the movable leg construction in a predetermined rigid relation with respect to said seat.

5. In a device of the class described the combination of a seat, leg means for the seat including a movable leg construction pivoted to the seat, a pair of spaced rack members providing upwardly extending teeth in spaced relation provided at opposite sides of the seat, a pawl frame pivotally carried by the movable leg construction providing a cross bar at one end thereof having stepped portions relatively offset forwardly of the seat for cooperation with one of said rack members and at the opposite end thereof providing rearwardly offset stepped portions for cooperation with the other rack member, said pawl frame being transversely adjustable with respect to the movable leg construction whereby to selectively position the stepped portions on said rack members.

6. In a combination device of the class described a seat including a pair of extensible sections, leg supporting means rigidly carried by one of said sections, back and leg supporting means pivotally carried by the other of said sections between the ends of said leg and back construction, a front retaining frame pivotally carried by the seat section to which said first mentioned leg construction is rigidly connected and adapted for swinging movement to adjustably lock the sections of said seat together, and

adjustable pawl and rack means carried by the other seat section and leg and back construction for supporting the latter in a predetermined relation with respect to said seat.

7. In a combination device of the class described a seat including extensible front and rear sections, leg supporting means rigidly carried by the front section, movable rear leg and back supporting means carried by the rear seat section, means for locking the seat sections in a desired adjustment, and means for locking the rear leg and back construction in a desired adjustment with respect to the rear section of said seat independent of the front section.

8. In a combination device of the class described a seat, leg supporting means for the seat, a back for the seat, a pivotally connected retaining frame carried at the front end of said seat including a pair of spaced members at the free end thereof spaced at different distances from the pivot axis of the frame, and means for limiting the upward swinging movement of the frame so that in its maximum extended position the member which is closest to the pivot axis of the frame will substantially align with the top of the back of said device.

9. In a combination device of the class described a seat including front and rear slidably connected extensible sections, leg supporting means for said sections, laterally extending pins carried by the front section, laterally extending pins carried by the rear section at the forward end thereof, a retaining frame for locking the said sections together pivoted to the front section at the forward end thereof adjacent said retaining pins of the front section, and hook means movable with said retaining frame including hooks for engaging the pins of the front section to limit the upward amplitude of swinging of the retaining frame, and hooks to engage the pins of the rear section to lock the front and rear sections of the seat together against displacement at a predetermined positioning of said retaining frame.

10. In a combination device of the class described a seat including extensible front and rear sections, a front leg construction rigid with the front section of said seat, a retaining frame pivotally connected at the front end of said seat having hooks adjacent the pivot ends thereof, pins carried by the rear section of said seat for engagement by said hooks when the retaining frame is swung upwardly and to limit the upward amplitude of movement of said frame to a slight rearward inclination from the vertical, said frame when so positioned locking the front and rear sections of said seat together, and a rear leg and back construction pivotally connected to said seat adapted at its upper end to be engaged by said retaining frame when the latter is

positioned as above mentioned to stably support the same.

11. In a combination device of the class described a seat including extensible front and rear sections, a front leg construction rigid with the front section of said seat, a retaining frame pivotally connected at the front end of said seat having hooks adjacent the pivot ends thereof, pins carried by the rear section of said seat for engagement by said hooks when the retaining frame is swung upwardly to limit the upward amplitude of movement of said frame to a slight rearward inclination from the vertical, said frame when so positioned locking the front and rear sections of said seat together, a rear leg and back construction pivotally connected to said seat adapted at its upper end to be engaged by said retaining frame when the latter is positioned as above mentioned to stably support the same, and rack and pawl means carried by the seat and said rear leg and back construction for locking the same in a desired angular relation at a point adjacent the pivot connection of the same.

12. In a combination article of the class described a seat, leg means for the seat including a movable leg construction movably connected to the seat, a rack carried by the seat including a plurality of spaced teeth, and a pawl frame movably carried by the movable leg construction in pivoted manner to permit its movement toward and away from the rack, said pawl frame having a series of stepped retaining portions thereon, and being movably carried so as to slide transversely of the line of teeth on said rack to permit the stepped portions of the pawl frame to selectively connect with the teeth whereby to fixedly position the movable leg construction in a desired angle of adjustment with respect to the plane of said seat.

13. In a combination household article of the class described a seat including a pair of extensible sections, a front leg construction carried by one of said sections rigid therewith, a rear leg and back construction pivoted intermediate its ends to the other seat section, and a retaining member pivoted adjacent the front of said seat including means to lock said sections of the seat in collapsed position and to engage the upper end of the rear leg and back construction to hold the latter inclined forwardly, said rear leg and back construction having rungs thereon similar to a step ladder.

14. In a combination household article of the class described a seat, leg supporting means for the seat, including a rear hinged-ly connected leg portion having a cross brace thereon, a back for the seat connected with said rear leg portion for movement therewith and having cross braces thereon, a piv-

totally connected retaining frame carried at the front end of said seat including a pair of spaced members at the free end thereof spaced at different distances from the pivot axis of the frame, means for limiting the upward swinging movement of the frame so that in its maximum extended position the member closest to the pivot axis of the frame will substantially align with the top of the back of said device when the back is inclined

over the seat, and means carried by the upper end of said back to engage the member which is most remote from the pivot axis of said frame with the latter slightly inclined rearwardly over the seat and with the rear leg portion and back at an inclined position so that the cross braces thereof serve as steps.

HENRY C. EMRICH.
